TOASTER ATTACHMENT FOR CAMP STOVES
 Robert A. B. Lang, 340 McNab Ave., Renfrew,
 Ontario, Canada
 Filed May 8, 1961, Ser. No. 108,678
 5 Claims. (Cl. 99—393)

This invention relates to a toaster attachment for camp stoves.

Many attempts have been made in the past to provide an attachment for making toast in conjunction with gas burners such as are employed in camp stoves. However, none of such attachments are in widespread use largely because, it is believed, they fail to produce satisfactory results or because they are unwieldy and awkward in operation.

It is an object of this invention to provide a toaster attachment for camp stoves which is simple and inexpensive in manufacture, which is compact in form for ease of storage and handling, which is subject to easy erection for use, which may be employed to produce toast of high quality, and which is readily adaptable for incidental uses.

The invention will be described with reference to the accompanying drawings, in which

FIGURE 1 is a perspective view of a camp stove with the attachment of the present invention associated therewith,

FIGURE 2 is a partial perspective view of the camp stove showing use of a portion of the attachment as a hot plate,

FIGURE 3 is a perspective view of one part of the attachment,

FIGURE 4 is a perspective view of another part of the attachment,

FIGURE 5 is a perspective view of the attachment in disassembled relation for packing or storage,

FIGURE 6 is an elevation of one end of the attachment,

FIGURE 7 is an elevation of the other end of the attachment, and

FIGURE 8 is a perspective view of the attachment in another position thereof for use as an oven.

Referring to the drawing, 1 is a conventional camp stove having a casing 2, a primary gas burner 3, a secondary gas burner 4, a grid 5 overlying the burners and composed of longitudinal rods 6 and transverse rods 7, and a gasoline supply tank 8.

The attachment of the present invention is indicated generally at 9 and comprises two closely similar parts 10 and 11 formed of suitable sheet metal.

Part 10 comprises a substantially flat rectangular main wall 12 and flat side walls 13 and 14 extending perpendicularly from the side edges of the wall 12 to form a channel-shaped structure substantially U-shaped in cross-section. The wall 12 has a free bottom edge 15 and a free top edge 16. Wall 12 has a relatively short slot 15a extending perpendicularly from the bottom edge 15 thereof adjacent side wall 13. Side wall 13 has an end edge 18 extending angularly from its junction with bottom edge 15 of the main wall and an end edge 19 extending angularly from its junction with top edge 16 of the main wall. Side wall 13 has a free longitudinal edge 20, a slot 20a extending inwardly from edge 18 and an inwardly offset shoulder 22 adjoining edge 20.

Side wall 14 has an end edge 23 extending angularly from its junction with bottom edge 15 of the main wall and an end edge 24 extending angularly from its junction with top edge 16 of the main wall. Wall 14 also has an inwardly offset shoulder 25 adjoining its free longitudinal edge 26 and a slot 26a extending inwardly from such shoulder.

2

The end edges 19 and 24 are flared inwardly to form flanges 27 and 28. Preferably, also, the top edge 16 of the main wall is flared slightly outwardly at 29.

Moreover, a reinforcing and protective baffle 30 is desirably mounted on the inner surface of main wall 12 along the bottom edge 15 and in slightly spaced relation to such inner surface. It will be observed that the baffle is slotted at 31 to correspond with slot 15a.

Part 11 is very closely similar to part 10 and has corresponding elements including main walls 32, side walls 33 and 34, bottom and top edges 35 and 36 of the main wall, slot 35a, end edges 38 and 39 and longitudinal edge 40 of side wall 33, slot 40a and shoulder 42 in side wall 33, end edges 43 and 44 and longitudinal edge 45 of side wall 34, and slot 45a and shoulder 47 in side wall 34. Part 11 also has an outwardly flared portion 48 of main wall top edge 36 and a protective baffle 49. However, the longitudinal edges 40 and 45 of the side walls are not flanged. Moreover, the distance between side walls 33 and 34 is shorter than the distance between side walls 13 and 14 by approximately twice the thickness of the metal sheet forming such walls whereby part 11 may nest within part 10 with the outer surfaces of its side walls 33 and 34 in engagement with the inner surfaces of side walls 13 and 14 of part 10.

As clearly shown in the drawings, the flanged edges 19 and 24 of part 10 and the corresponding edges 39 and 44 of part 11 extend at an acute angle to the plane of the corresponding main wall 12 or 32. Thus, parts 10 and 11 may be associated together, as shown in FIGURES 1, 6 and 7 to form a generally pyramidal casing with the flanges 27 and 28 acting to retain the parts in such association. It will be apparent that the casing forms a chamber with a widely flared bottom opening and a narrow slotlike top opening which is indicated at 50.

Mounted on the outer surface of each main wall 12 and 32 is a bread-receiving grill 51. This grill may be fixed to the wall in slightly spaced relation thereto and is provided with a lower bread supporting shelf 52. As shown, the grill may be removably mounted on the wall for ease of manufacture and storage and swingable for convenience in use. To this end, a rod 53 carries the grill and may be mounted on the wall by means of a pair of lugs 54 on the wall. A handle portion 55 on the end of the rod permits swinging of the grill. Parallel heat-dissipating discs 55a may be provided on each rod 52 adjacent handle portion 55.

In use, the attachment is erected in the form shown in FIGURES 1, 6 and 7, and is placed over the primary burner 3 of the stove, as indicated in FIGURE 1. It is firmly positioned on the grid 5 by reception of a longitudinal rod 6 thereof in slots 15a and 35a and transverse rods 7 in slots 20a, 26a and 40a, 45a. With the burner in operation, toast may now be produced.

It is important, for the purposes of the invention, that a venturi type of chamber be formed over the burner whereby the flame therefrom uniformly heats the main walls 12 and 32 of the device. As a result, the toast produced is of uniform high quality.

When not in use, the parts 10 and 11 may be nested, as shown in FIGURE 5, with the main walls 12 and 32 in abutting relation. In this position, the attachment is readily receivable in the main stove casing 2 for storage purposes. This is an important advantage in providing means for transporting the attachment while ensuring that it is always conveniently available for use.

The attachment is useful for other purposes in association with the stove. Thus, as shown in FIGURE 2, one part 11 (or 10) may be fitted over the secondary burner 4 and positioned thereon by reception of a rod 6 in slots 40a and 45a and main wall 32 overlying the burner. It

may thus be used as a warming plate for reception of a pan or plate which would be supported in spaced relation to wall 32 by the protruding edges of the lugs 54 and the edge 36.

As shown in FIGURE 8, the parts 10 and 11 may be associated together with the side walls 13, 14 and 33, 34 in lapped relation and the main walls 12 and 32 in parallel, spaced relation to provide an open-ended warming oven 56. As shown, wall 32 of part 11 rests on edge 20 of wall 13 of part 10, while edge 45 of wall 34 of part 11 rests on wall 12 of part 10. The device in this position is simply laid upon the grid 5 overlying the secondary burner 4.

There has thus been provided a practical accessory for a camp stove which has useful and effective utility and which is highly convenient in operation.

The device may be readily handled when hot by providing hook-receiving holes 57 in the main walls 12 and 32.

It will be understood that by the expression "gas burner" is intended to mean any burner that employs any form of combustible gas or vapor.

I claim:

1. A toaster attachment for gas burners comprising first and second sheet metal parts each comprising a flat rectangular main wall and a pair of side walls extending angularly from said main wall, each said side wall having a free end edge disposed at an acute angle to the plane of said main wall, each said free end edge extending from a point adjacent to but spaced from said main wall to a point remote from said main wall, said free end edges of each said pair of side walls being in opposed relation, each said free end edge of said first part having a flange thereon directed inwardly towards the other of said

flanges, said second part having each of its side walls disposed between the side walls of said first part and in substantial abutment with one of said last-mentioned side walls, said flanges of said first part being in overlying relation to said main wall of said second part to releasably retain said parts together, each said main wall having a free top edge, said top edges being spaced from each other to form an opening therebetween, said main walls extending from said opening in diverging relation to each other.

2. A toaster attachment as defined in claim 1, each of said side and main walls having a bottom edge, each of said bottom edges having a grid-receiving slot extending inwardly therefrom.

15 3. A toaster attachment as defined in claim 1, each of said main walls having a grill mounted on the external surface thereof.

4. A toaster attachment as defined in claim 2, including a reinforcing plate mounted on the inner surface of each said main wall, said plate being disposed in substantially parallel, spaced relation to said main wall and extending from one of said side walls to another of said side walls, said plate having a lower edge in adjacent relation to said bottom edge of said main wall.

25 5. A toaster attachment as defined in claim 1, each said main wall having a portion adjoining said top edge thereof flared outwardly away from the other of said main walls to provide a throat leading to said opening.
